DESIGN FOR A TIRE

Arthur Balthazar and John E. Allen, Chicopee Falls, Mass., assignors to Gamble Stores, Inc., Minneapolis, Minn., a corporation of Delaware

Application March 4, 1935, Serial No. 55,718

Term of patent 14 years

To all whom it may concern:

Be it known that we, Arthur Balthazar and John E. Allen, citizens of the United States, residing at Chicopee Falls, county of Hampden, and State of Massachusetts, have invented a new, original, and ornamental Design for a Tire, of which the following is a specification, reference being had to the accompanying drawing, forming part thereof.

Fig. 1 is a fragmentary perspective view of a pneumatic tire having a tread design embodying

our invention shown thereon, the complement of the tire being indicated by dotted lines;

Fig. 2 is a fragmentary plan view of the tire; and

Fig. 3 is a cross-sectional view taken substantially along the line 3—3 on Fig. 2.

We claim:

The ornamental design for a tire as shown.

ARTHUR BALTHAZAR.
JOHN E. ALLEN.
